UNITED STATES PATENT OFFICE.

JOSEPH J. DICKMAN, OF BROOKLYN, NEW YORK.

DIAL TELEPHONE.

Application filed April 7, 1926. Serial No. 100,218.

This invention relates to dial telephones and has as an object to provide an attachment for the dials customarily supplied by telephone companies, by means of which the 5 dialing operation may be performed rapidly and conveniently.

Other objects and advantages of the invention will appear hereinafter.

A preferred embodiment of the invention 10 selected for purposes of illustration is shown in the accompanying drawings, in which,

Figure 1 is a top plan view of a common type of dial showing the apparatus of the invention attached thereto.

15 Figure 2 is a side elevation on the line 2—2 of Figure 1.

Figure 3 is a perspective view of the device removed from the dial.

Telephone dials of the type referred to 20 herein ordinarily comprise a base 1 having a disk 2 secured thereto, and disk carrying numerals or other indicia 3. Rotatably mounted on the base 1 above the plate 2 is a second disk 4 having a series of apertures 25 5 therein which expose the indicia on the disk below. A fixed stop 6 is provided which is customarily attached to the fixed disk 2.

In normal operation in calling a desired 30 station the user of the telephone inserts the index finger into the aperture of the disk 3 which exposes the number which it is desired to call and then, using the finger as a pivot, rotates the disk 3 in a clockwise direction toward the fixed finger piece 6 until stopped thereby. Thereafter the finger is removed and the disk 3 returns to normal position under the influence of a suitable spring. If a succession of numbers are to 35 be called, this process is repeated until the proper impulse is transmitted to the switching apparatus.

According to the present invention it is proposed to provide an attachment by which 45 this dialing operation may be performed without using the finger as a pivot. For this purpose, it is proposed to provide means to frictionally engage a suitable part of said rotatable disk 4, and to pivotally mount 50 thereon an arm carrying a knob adapted to engage any of the apertures 5 and a handle by which the disk may be rotated.

Dials of the type illustrated are commonly provided with a cap 7 fixed to the disk 4 55 and rotating therewith, said cap usually carrying indicia such as the station num-

ber. In the preferred embodiment of the invention illustrated herein, it has been found convenient to provide means to frictionally engage said cap and accordingly a strip of metal 8 is provided to span cap 7, said strip having its ends bent downwardly to provide flanges 9 and 9' to frictionally engage the outer periphery of the cap. Pivoted to the strip 8 at the center thereof and coincidently with the axis of rotation of said disk 4 is an arm 10 preferably of spring metal, said strip carrying at its outer end a knob 11 adapted to engage the apertures of the disk 4 and a handle 12 by means of which the device may be operated. Preferably a washer 13 surrounds the pivot to normally hold the knob 11 in raised position above and out of engagement with said disk.

When it is desired to call a number the 75 knob 11 is swung by the handle 12 to a position above the proper aperture of the disk 4 and is then depressed to engage said aperture. The disk is then rotated in a clockwise direction by the handle until stopped by the finger piece 7. If the handle is then released, the disk returns to normal position in the usual manner. In calling a succession of numbers, the knob is successively swung to engage the proper apertures. 85

It will be observed that the device may be attached to and removed from the dial without any modification or mutilation thereof.

It is to be understood that the invention 90 may be variously modified and embodied within the scope of the subjoined claims.

I claim as my invention:

1. An attachment for telephone dials having a rotatable disk provided with apertures, 95 comprising, means adapted to frictionally engage said disk, and means pivotally mounted thereon to engage said apertures to rotate said disk.

2. An attachment for telephone dials having a rotatable disk provided with apertures, comprising, means adapted to frictionally engage said disk, and an arm pivotally mounted thereon, said arm being provided with a knob adapted to engage said apertures and a handle by means of which said arm and disk may be rotated. 105

3. An attachment for telephone dials having a rotatable disk provided with apertures, comprising, means adapted to frictionally engage said disk, and an arm pivotally mounted thereon, said arm being of spring 110

metal and provided with a knob adapted to engage said apertures, said parts being constructed and arranged to normally hold said knob above said disk.

5. An attachment for telephone dials having a rotatable disk provided with apertures, comprising, means adapted to frictionally engage said disk, and an arm mounted thereon on a pivot whose axis is substantially coincident with the axis of rotation of said disk, said arm being provided with a knob to engage said apertures.

6. An attachment for telephone dials having a rotatable disk provided with apertures, comprising, a metal strip having flanges to frictionally engage said disk, an arm mounted thereon on a pivot whose axis is substantially coincident with the axis of rotation of said disk, said arm being of

20 spring metal and provided with a knob to

engage said apertures, said parts being constructed and arranged to hold said arm and knob normally above said disk.

6. An attachment for telephone dials having a rotatable disk provided with apertures near its periphery and a flanged circular member projecting from within the circle of said apertures, comprising means adapted to frictionally engage said flanged member, and an arm pivotally mounted thereon with its axis substantially coincident with the axis of rotation of the dial, said arm being provided with a knob adapted to engage said apertures and a handle by means of which said arm and dial may be rotated.

In testimony whereof, I have signed my name to this specification this 25th day of March, 1926.

JOSEPH J. DICKMAN.
